United States Patent Office.

JOHN FRASR, OF DOWAGIAC, MICHIGAN.

Letters Patent No. 68,178, dated August 27, 1867.

IMPROVED SMOOTHING-IRON.

The Schedule referred to in these Letters Patent and making part of the same.

TO ALL WHOM IT MAY CONCERN:

Be it known that I, JOHN FRASR, of Dowagiac, in the county of Cass, and State of Michigan, have invented a new and improved Smoothing-Iron; and I do hereby declare that the following is a full, clear, and exact description thereof, which will enable others skilled in the art to make and use the same, reference being had to the accompanying drawings, forming part of this specification.

This invention relates to an improved smoothing-iron, and consists in having the smoothing surface of copper, attached to the body of the iron by rivets cast with the copper plate.

My improved smoothing-iron requires less fuel to heat, and retains the heat longer than the ordinary iron, can receive a much higher polish, whereby a much smoother surface is obtained than the ordinary iron, and the starch will not adhere to its surface. It is not liable to rust, nor to iron-mould the linen, to which it imparts a far higher gloss than the ordinary iron.

The accompanying drawing shows my improved iron in section.

A is the ordinary smoothing-iron, cast with holes *a a* to receive the rivets *b b* cast with the copper plate B.

I claim as new, and desire to secure by Letters Patent—

The copper plate B, in combination with a smoothing-iron, in manner and for the purposes substantially as described.

JOHN FRASR.
